F. C. TRIMBACH

DOORSTOP

Filed July 28, 1924

UNITED STATES PATENT OFFICE.

FRANK C. TRIMBACH, OF DAYTON, OHIO.

DOORSTOP.

Application filed July 28, 1924. Serial No. 728,660.

My invention relates to door stops and more particularly to a door brace adapted to hold the door in its open or partially open position as well as secure the door when closed.

In the present construction there is contemplated a vertically movable reciprocatory bolt member secured to the lower portion of a swinging door, such as a garage door, barn or factory door, which bolt is operated by an oscillatory control lever mounted at a convenient height upon the door, and to which the bolt is connected by an intermediate link. The reciprocatory bolt member is locked at either limit of its stroke by the movement of the hand lever beyond dead center position in one direction or the other. The bolt engages a keeper in the door sill when projected downward to secure the door in closed position. The bolt is preferably provided with a series of rack teeth engaging a pivotally mounted gear sector or toothed head which carries a brace rod. As the bolt is retracted by the movement of the hand lever to disengage it from the keeper the toothed head or gear sector is oscillated by its engagement with the rack teeth upon the bolt to swing the brace rod from an upwardly extending retrieved position to a downwardly inclined position in which the brace rod will drag upon the ground or upon the floor as the door swings open preventing the return movement of the door by its thrust engagement with the ground or floor. As a modification of this construction, a medially pivoted arm or lever, to one end of which the actuating link may be connected and upon the opposite end of which the brace arm is supported, may be employed in lieu of the gear sector or toothed head.

The object of the invention is to simplify the structure as well as the means and mode of operation of door stops and swinging closure fasteners, whereby they will not only be cheapened in construction, but will be more efficient in use, positive in operation, uniform in action, easily controlled, and unlikely to get out of repair.

A further object of the invention is to provide a door stop which will securely hold a swinging door in different positions of adjustment to prevent its closing movement.

A further object of the invention is to provide means for engaging and disengaging

the door stop without the necessity of stooping and by which the stop may be locked in its operated or retracted position.

A further but none the less important object of the invention is to provide such door stop mechanism, the parts of which are so designed and arranged as to be cheaply and economically manufactured with minimum machine operation.

With the above primary and other incidental objects in view as will more fully appear in the specification, the invention consists of the features of construction, the parts and combinations thereof, and the mode of operation or their equivalents as hereinafter described and set forth in the claims.

In the accompanying drawings, wherein is shown the preferred, but obviously not necessarily the only form of embodiment of the invention, Fig. 1 is a perspective view of a portion of a swinging door, illustrating the door stop forming the subject matter hereof applied thereto. Figs. 2 and 3 are a front and a side elevation respectively of the door stop and operative parts. Figs. 4 and 5 illustrate two modifications of the brace arm mounting wherein an oscillatory lever is employed to carry the brace arm in lieu of the segmental gears.

Like parts are indicated by similar characters of reference throughout the several views.

The present invention is primarily designed for use upon swinging garage doors, barn doors, warehouse doors, farm gates and other swinging closures, which it may be desirable to temporarily secure in their open or partially open position. However, the invention is not limited to such use but may be applied to any movable member or structure, the retrograde movement of which is to be prevented. The member to be stopped need not be swingingly mounted, but may be a reciprocatory body. The brace arm in this case operates somewhat as a pawl permitting free movement of the door, gate or other object in one direction, but automatically preventing its return. In the drawings, 1 is a portion of a swinging door, to the lower inner face of which is secured a guide mounting or bracket 2, in which is mounted for reciprocatory movement a vertically slidble bolt 3. When depressed the

- bolt 3 preferably, tho not necessarily, projects below the lower margin of the door for engagement with a keeper or socket in the door sill. Thus when depressed such bolt 3 5 serves to lock the door in its closed position. The bolt 3 is raised and lowered by means of a hand lever 4 pivoted at 4' to an upper portion of the door 1. As a convenient method of mounting a plate 5 is provided, 10 from which projects a trunnion stud to receive the hand lever 4. Pivots connected at its upper end to the extremity of the operating lever 4 and at its lower end to the reciprocatory bolt 3 is an intermediate 15 link 7. The link 7 is bent laterally at a point closely adjacent to its connection to the operating lever 4, and the lever 4 is undercut or recessed at one side of its pivotal connection as shown at 8 to enable the 20 pivotal connection of the link 7 with the extremity of the lever 4 to be moved slightly beyond dead center position, thereby locking the reciprocatory bolt 3 in its elevated position. 25 Upon reverse movement of the lever 4, by which the bolt 3 is depressed, the pivotal connection of the link and lever moves in the opposite directions slightly beyond dead center position, thereby again locking the bolt 3 30 at the opposite limit of its travel. The face of the bolt 3 within the guide mounting 3 is provided with a series of rack teeth 11. Pivots mounted in ears 12 projecting from the bracket or guide mounting 2 is a 35 gear sector 13, the teeth of which intermesh with the rack teeth 11 of the reciprocatory bolt. Fixedly secured to the oscillatory gear sector 13 is a brace arm 14. As the bolt 3 is depressed by the manipulation of the 40 hand lever 4, the gear sector 13 is oscillated by its engagement with the rack teeth 11, thereby turning the brace arm 14 upwardly to approximately parallel relation with the door. 45 Upon reverse movement of the control lever 4 by which the lower extremity of the bolt 3 is disengaged from the keeper or socket in the door sill, the gear sector 13 is oscillated in reverse direction carrying with it the brace arm 14, into a downwardly inclined position. In this position the brace arm 14 operates somewhat as a pawl dragging freely over the ground, floor or other surface over which the door swings as the 50 door is opened. However, upon closing movement of the door, the brace arm effects thrust engagement with the ground or floor, resisting return swinging movement of the door until the operating lever 4 is reversed. 55 The brace arm 14 and reciprocatory bolt 3 alternate operative positions. That is to say, when the brace arm 14 is in operative position to prevent the closure of the door, the bolt 3 is retracted. To the contrary 60 65 when the brace arm 14 is fully retrieved the

bolt is in its depressed position in which it engages the keeper or socket in the door sill to prevent the opening of the door.

In lieu of the geared operative connection for the brace arm 14, there is shown in Fig. 4 a tilting lever 15, pivoted in a suitable supporting bracket 16 similar to the bracket 2. The motion transmitting link 7 is connected to one end of the tilting lever 15, while the brace arm 14 is pivotally supported from the opposite end. The oscillation of the control lever 4 effects a corresponding oscillation of the tilting lever 15 to raise and lower the brace arm. While the tilting lever 15 is shown medially pivoted in Fig. 4, there is shown in Fig. 5 a further modification wherein the tilting lever is pivoted at its extremity to the supporting bracket 16, and the motion transmitting link 7 is connected at the medial point. The general operation, however, is the same in both instances. When the end of the swinging lever 15 carrying the brace arm 14 is swung upwardly by the adjustment of the hand lever 4 and the link 7, the lower end of the brace arm 14 will be elevated slightly above the lower margin of the door, thus freeing it from the ground or floor over which the door swings and permitting free movement of the door to and fro. However, upon reversal of the control lever and the tilting lever 15, the brace arm 14 is lowered to a position wherein it will drag upon the ground or floor as the door is open, assuming an inclined position, and upon reverse movement of the door effecting thrust engagement with the ground or floor to resist the closure of the door. To afford a limited knuckle movement of the lever 15 and brace arm 14 by which the relative movement in one direction will be limited, the upper end of the brace arm 14 after being passed thru a perforation in the end of the swinging lever 15 is extended a short distance parallel with the plane of the lever, as shown at 17, and is then bent laterally at 18, across the lever 15, to afford a limiting stop. By this construction, the brace arm swings free as the lever 15 is elevated, but upon lowering of the swinging lever 15, into operative position, the brace arm and lever will interlock to afford a stiff thrust resistant connection.

From the above description it will be apparent that there is thus provided a device of the character described, possessing the particular features of advantage before enumerated as desirable, but which obviously, is susceptible of modification in its form, proportions, detail construction and arrangement of parts, without departing from the principle involved or sacrificing any of its advantages.

While in order to comply with the statutes, the invention has been described in language more or less specific as to structural features,

it is to be understood that the invention is not limited to the specific details shown, but that the means and construction herein disclosed comprises the preferred form of 5 several modes of putting the invention into effect, and the invention is, therefore, claimed in any of its forms or modifications within the legitimate and valid scope of the appended claims.

10 Having thus described my invention, I claim:

1. In a door stop, a brace rod adapted to drag upon the floor or ground idly as the door is opened permitting free movement of 15 the door in one direction when said brace rod is in operative position, but adapted by its thrust engagement with the ground or floor to prevent the return movement of the door, a pivotal mounting for said brace rod, 20 permitting the movement of the rod to and from operative positions, and a door stop for holding the door against free movement a reciprocatory link simultaneously controlling the adjustment of the rod and stop, and 25 a pivoted operating handle to which the link is connected, the pivoted handle being adjustable beyond dead center positions at the opposite limits of its range of movement to lock said brace rod and stop in their operative and inoperative positions.

2. In a door stop, a reciprocatory bolt for locking the door in closed position, a second member for locking the door in open position, operative connections between the respective locking members, whereby the movement of either member to locking position retracts the other and vice versa, and actuating means common to both members.

3. In a door stop, a reciprocatory rack 40 bar, a bolt head carried by the rack bar engageable with a corresponding keeper for locking the door in a predetermined position of adjustment, a swinging arm engageable with the floor or ground for securing 45 the door in other positions of adjustment, a gear sector by which the swinging arm is carried, said sector meshing with the reciprocatory rack bar and oscillated by the reciprocation thereof, and means for actuating the rack bar.

4. In a door stop, two alternately operable locking devices, one of which locks the door in closed position and the other of which locks the door in open position, and 55 actuating means common to both locking members by the operation of which the locking members are alternately engaged and retracted.

5. In a door stop, two alternately operable locking devices, one of which locks the door in closed position and the other of which locks the door in open position, and a pivoted actuating lever operatively connected with said locking members, said actuating lever being movable beyond the

dead center position at opposite limits of its range of movement to secure said locking members in their operative and retracted positions.

6. In a door stop of the character described, an elongated grooved mounting to be secured to the lower portion of a door, a reciprocatory slide mounted therein and provided with a series of rack teeth, ears on said grooved slide, a gear segment pivotally mounted in said ears and intermeshing with the rack teeth of said slide, and a brace arm directly connected with the gear segment and operable therewith into and out of engagement with the surface over 80 which the door swings, and means for locking the slide at the opposite limits of its range of movement.

7. In a door stop of the character described, a reciprocatory rack bar, a mounting therefor, a gear segment carried by the mounting and intermeshing with the rack bar, a stop carried by the gear segment in substantially radially disposed relation and in the plane of the segment, said arm being 90 turned to and from operative engagement with the surface over which the door swings by the reciprocation of the rack bar and means for locking the rack bar in its operated position in either direction.

8. In a door stop of the character described, a reciprocatory rack bar, a mounting therefor, a gear segment having intermeshing engagement with the rack bar, a stop brace actuated thereby to and from 100 operative engagement with the surface over which the door swings, the reciprocation of the rack bar, the surface over which the door swings having therein a socket in which the end of the rack bar engages when reciprocated in one direction to hold the door against swinging movement.

9. In a door stop of the character described, a reciprocatory lock bolt carried by the door and engageable in a socket in the 110 surface over which the door swings and a second stop member operatively connected therewith and automatically actuated into engagement with such surface by the retraction of the lock bolt and vice versa.

10. In a door stop of the character described, a door stop engaging the surface over which the door swings permitting free movement of the door in one direction but automatically preventing the return movement of the door, and a second stop member engageable with such surface to prevent said free swinging movement, and interconnections between said stops whereby the retraction of one will operatively set the 120 other.

In testimony whereof, I have hereunto set my hand this 25th day of July A. D. 1924.

FRANK C. TRIMBACH.
